Kevin Prince(57) **CLAIM**

I claim the ornamental design for an electronic arc lighter, as shown and described.

DESCRIPTION

FIG. 1 is a top perspective view of an arc lighter, showing my new design with a top in a closed position;

FIG. 2 is a bottom perspective view of FIG. 1;

FIG. 3 is a front elevational view of FIG. 1;

FIG. 4 is a rear elevational view of FIG. 1;

FIG. 5 is a right-side elevational view of FIG. 1;

FIG. 6 is a left-side elevational view of FIG. 1;

FIG. 7 is a top plan view of FIG. 1;

FIG. 8 is a bottom plan view thereof, illustrated with the top in an open position;

FIG. 9 is a front perspective view of FIG. 8;

FIG. 10 is a front elevational view of FIG. 8;

FIG. 11 is a rear elevational view of FIG. 8;

FIG. 12 is a right-side elevational view of FIG. 8; and,

FIG. 13 is a top plan view of FIG. 8.

The broken lines showing a logo in FIGS. 1, 3, 9 and 10 and the broken lines in FIG. 4 depict portions of the lighter that form no part of the claimed design.
